UNITED STATES PATENT OFFICE.

CHARLES EDWIN SPROULS, OF HEREFORD, TEXAS.

DIVISION-BLOCK FOR BALING-PRESSES.

993,897.

Specification of Letters Patent. Patented May 30, 1911.

Application filed March 16, 1910. Serial No. 549,680.

To all whom it may concern:

Be it known that I, CHARLES E. SPROULS, a citizen of the United States, residing at Hereford, in the county of Deaf Smith and 5 State of Texas, have invented a new and useful Division-Block for Baling-Presses, of which the following is a specification.

This invention relates to division blocks for baling presses and has for its object the 10 provision of a simple construction whereby the life of the block will be increased and the baling wire may be readily inserted or withdrawn. This object and such other incidental objects, as will hereinafter appear, are attained by the use of the device 15 illustrated in the accompanying drawings, and the invention consists in certain novel features of the same which will be herein-after described and claimed.

20 In the drawings, Figure 1 is an elevation of a portion of a baling press showing division blocks in position therein equipped with my improvements. Fig. 2 is an enlarged end elevation, partly broken away, 25 of one of the division blocks. Fig. 3 is a detail perspective view of the wire guide and support.

The division block 1 consists of a wooden body 2 of the usual construction and of such 30 dimensions as to fit snugly within the baling chamber 3 of a baling press so as to separate the bales formed therein and to hold the same in proper shape during the application of the bale ties. The bale ties 4 are 35 passed around the bales in the usual manner and are inserted through wire guides or supports 5 on the sides of the body 2 of the division block, as clearly shown in Fig. 1. These wire guides or supports 5 are castings 40 consisting of a back plate 6 corresponding in length to the width of the division block and secured to the side of the same by means of screws 7 inserted through openings 8 at the corners of the casting, as shown, and 45 as will be readily understood. The casting may be secured to the face of the body 2 or may be set within recesses therein, as shown in Fig. 2, and on the outer face of the casting are outwardly-converging ribs or 50 plates 9 together forming a channel or groove 10 through which the tie wire 4 is inserted, the space or opening 11 between the outer edges of these plates 9 being of such size as to easily permit the wire to be 55 withdrawn after the bale is tied and at the same time prevent its premature withdrawal.

The spaces between the castings 5 are filled by strips 12 secured to the body 2 of the division block and properly shaped to fit snugly against the castings so as to entirely 60 fill the space between them and having their outer faces flush with the outer edges of the converging plates or ribs 9 of the casting.

It will be seen from the foregoing description, taken in connection with the accompanying drawings, that I have provided a very simple, cheap and efficient device by which rough wire may be inserted through the grooves of the division blocks without bending the wire or defacing the block, inasmuch as the wire will be passed between metallic surfaces into which it cannot enter and will, consequently, be forced to pass directly to the opposite side of the block. Slight irregularities in the wire will, consequently, not interfere with its passage through the grooves, as the walls of the casting will be sufficiently strong to overcome these irregularities and tend to straighten the wire in its passage to the opposite side 80 of the baling chamber. The division blocks heretofore in use would quickly split under the pressure to which they were subjected so that the insertion of the tie wires required considerable time and was a difficult 85 operation, but these objections are entirely overcome by the use of my device for the reasons stated. The casting reinforces the edges of the grooved portions of the block 90 so as to effectually resist the battering of the same under the action of the baling press so that the filling strips 12 will not be broken or splintered easily, and should these filling strips be damaged through long continued 95 use, they may be replaced without requiring the provision of an entirely new division block.

The device may be made in any size and, in actual practice, will be made in a large 100 variety of sizes so that it may be easily applied to any style and size of baling press.

Inasmuch as I employ a solid casting, the block is braced and held together and the inadvertent admission of a hard substance between the plunger of the press and the division block will not have any damaging effect on the division block, as the metallic casting will effectually protect the same and prevent the destruction of the wire-receiving groove. The straw will not press into the groove, and, if one or two straws should happen to find their way into the grooves,

their presence will not interfere with the passage of the wire. The casting is secured positively to the central body of the division block and, consequently, slight inaccuracies 5 in the shaping and fitting of the filling strips between the castings will be of no importance, inasmuch as they do not perform any function in the holding of the casting.

From the foregoing description, taken in 10 connection with the accompanying drawings, the advantages of the construction and of the method of operation will be readily apparent to those skilled in the art to which the invention appertains, and while I have 15 described the principle of operation of the invention, together with the device which I now consider to be the best embodiment thereof, I desire to have it understood that the device shown is merely illustrative, and 20 that such changes may be made when desired as are within the scope of the claims appended hereto.

Having thus described the invention, what I claim as new, and desire to secure by Letters Patent, is:—

1. A division block comprising a body member, wire guides secured thereto, each comprising a back plate having means for the passage of fastening devices there- 30 through into the body member, and spaced

outwardly converging rigid ribs projecting from said plate in inset relation to the outer edges of the back plate, said ribs defining a dove-tail shaped channel with a space between the outer edges of the ribs of a size to 35 permit withdrawal of a baling wire on the exertion of a suitable force, and fillers applied to the body portion of the block with their outer faces flush with the outer edges of the converging ribs. 40

2. In a division block for baling presses, wire guides each consisting of a back plate of rigid material with rigid converging ribs formed thereon in inset relation to the margins of the back plate where joining the latter, the portions of the back plate projecting beyond the ribs being provided with means for the passage of fastening devices and the outer edges of the converging ribs being spaced apart to permit the passage of a baling wire therebetween but prevent its premature passage. 45 50

In testimony, that I claim the foregoing as my own, I have hereto affixed my signature in the presence of two witnesses.

CHARLES EDWIN SPROULS.
